PLUG HOUSING

Jack L. Bowen, Larry G. Fischer, and James Ryan,
Waseca, Minn., assignors to E. F. Johnson Company,
Waseca, Minn.

Filed June 20, 1972, Ser. No. 264,424

Term of patent 14 years

Int. Cl. D13—03

U.S. Cl. D26—1 B

FIG. 1

FIG. 2

FIG. 3

FIG. 4

FIG. 5

FIG. 6

FIG. 1 is a front elevational view of a plug housing, showing our new design;

FIG. 2 is a side elevational view thereof;

FIG. 3 is a rear elevational view of the plug housing shown in FIG. 2;

FIG. 4 is a bottom plan view of the plug housing shown in FIG. 2, it being understood that the top is substantially a mirror image of the bottom shown herein;

FIG. 5 is a side elevational view opposite to that shown in FIG. 2, and rotated 180° about the horizontal axis of the plug housing; and

FIG. 6 is a front perspective view of the plug housing.

We claim:

The ornamental design for a plug housing, as shown and described.
